SHOE SEWING MACHINE

Hubert Boothroyd, Leicester, England, assignor
to United Shoe Machinery Corporation, Flem-
ington, N. J., a corporation of New Jersey

Application March 6, 1947, Serial No. 732,903
In Great Britain March 30, 1946

30 Claims. (Cl. 112—48)

1

This invention relates to improvements in sewing machines for operating on thick heavy material, such as leather, and is particularly concerned with provision of an improved construction and operation of work feeding means for lockstitch shoe sole sewing machines of the type adapted for sewing a sole to a shoe bottom by a lockstitch seam passing through the sole to the interior of the shoe, the term shoe being used herein as including outer footwear generally.

The illustrative machine is, in certain respects, similar to the machine described in United States Letters Patent No. 2,331,118 granted October 5, 1943 on application of Gouldbourn and Kestell, but differs from that machine particularly in regard to the needle and awl actuating mechanism and to the means for feeding a shoe through the machine while it is being sewn thereby.

A machine constructed as described in said patent has proved in practice to be capable of producing very satisfactory sewing results while operating at a comparatively high speed of approximately 750 revolutions per minute, the machine then operating without undue noise or vibration. As described in said patent, however, the needle and awl remain constantly spaced apart a distance equal to a stitch length and move, in company, alternately to the left and to the right to cause the awl to move the work, to the left, over the horn or internal work support of the machine and then to bring the needle, to the right, into alignment with the hole made in the work by the awl, the work being held against movement during the movements of the needle and awl to the right by a presser foot.

With such an arrangement it is necessary that, whenever an adjustment is made in the extent of the work-feeding movement of the awl to bring about a variation in the length of stitch to be sewn, a corresponding adjustment shall be made in the spacing of the awl from the needle, otherwise the needle, when it enters the work will not enter the hole made for it by the awl. It is possible, when it is desired to sew short stitches, to adjust the awl toward the needle until the adjacent faces of their carrier levers almost abut against each other.

Since, however, needles and awls intended for operating on stout shoes have to be of a sturdy construction and have to be supported by robust carriers therefor, it is not possible, in a machine constructed as described in the aforesaid patent to bring the needle and awl as close together as is sometimes desired, bearing in mind the fact that shoe manufacturers sometimes wish to sew as

2

many as eight stitches to the inch when attaching soles to shoe bottoms.

Moreover the particular needle and awl supporting arrangements of the machine described in the prior patent impose an undesired restriction on the extent to which the needle and awl can be spaced apart and therefore limit undesirably the minimum length of stitch which can be sewn.

10 It is one of the various objects of the invention to improve a machine of the type referred to by providing it with novel and conveniently adjustable means for enabling it to sew stitches which vary considerably in length, for example for enabling it to sew from three to eight stitches to the inch.

15 It is another of the various objects of the invention to provide, in a sewing machine including a needle and a work-feeding awl operating in side by side relation at the same side of the work, a novel and simply constructed arrangement for enabling the awl to engage the work close to the work-penetrating path of the needle, prior to its feeding the work toward the needle, when stitches of relatively short length are to be sewn.

20 It is yet a further one of the various objects of the invention to provide, in a sewing machine including a curved hooked needle and a curved awl a novel and convenient arrangement whereby the needle and awl may be oscillated, in different paths, about the same axis toward and away from engagement with the work at certain times in a stitch forming cycle and whereby they may be caused to lie in one and the same plane at a desired stage in the stitch forming cycle.

25 Still another object of the invention is to provide in a sewing machine in which the work is fed through the machine by step by step movements of an awl or like member, novel and convenient means for effecting a variation in the extent of the work feeding movements and/or in the lengths of the stitches to be sewn.

30 With these objects particularly in mind, the illustrative machine hereinafter described makes use of a curved hooked needle which normally occupies a stationary position laterally of the machine along the line of work-feed but which oscillates about a transverse axis toward and away from the work, and a curved awl which also oscillates about the same axis but which has imposed on its oscillating movements, and in time relation to the oscillations of the needle, an idle lateral movement which brings its close by the side of the plane of movement of the needle when

the needle occupies a retired or retracted position and prior to the awl engaging the work and feeding it toward the needle.

When an awl is used to punch needle and thread-receiving holes in stout and thick leather in a machine which operates at a relatively high speed, it is desirable, and long experience proves that the awl should be as sturdy as possible, compatible with the desirability that the awl-holes formed in the work be filled by thread and that the awl move along its own length in piercing the work and not be thrust against the work in a direction inclined to its length; otherwise the awl will be deflected by the resistance to penetration offered by the work with consequent likelihood of breakage of the awl, and/or inaccurate handling of the work thereby.

It is moreover desirable to arrange both the awl and needle for oscillation rather than for reciprocation since it is possible in this way to reduce the weight of the parts and relatively high speed may be obtained without excessive noise or vibration. In complying with these various desiderata in the illustrative machine, hereinafter described, in which the needle and awl lie in parallel planes at the same side of the work and in which the awl feeds the work to the needle in each stitch forming cycle of the machine, provision is made for the awl not only to penetrate the work as close to the needle as required when sewing very small stitches but also then to move laterally toward the needle plane until the awl-hole in the work is carried directly beneath the needle point.

In the illustrative machine, hereinafter described, this provision includes means for moving the awl laterally with two separate movements, the first of which is bodily in the direction of work feed when the needle is retracted from the work and the awl is in a partially lowered position so that part of the awl carrier actually underlies the needle carrier enabling the awl to descend to pierce the work at a point close to the plane of the needle. By supporting the needle and awl in robust actuating arms bent somewhat toward each other and by arranging for the first lateral movement of the awl to occur idly without engaging the work when the needle-actuating arm is in an elevated position and the awl-actuating arm is in a partially lowered position, the awl-carrying end of the latter arm may be brought beneath the needle-actuating arm and the awl may therefore be brought close to the plane in which the needle lies.

The awl-actuating mechanism of the illustrative machine is arranged to cause the awl to penetrate the work on the conclusion of the idle lateral movement above referred to and then to begin its second bodily movement in the direction of work feed carrying the work with it, until the awl-hole comes directly into alignment with the needle path for entry by the needle when it descends. Having brought the awl-hole into alignment with the needle path, the awl pauses there while the presser foot descends and clamps the work against the internal work support. While the work is being held by the presser foot, the awl retracts sufficiently to withdraw it from the work, then steps laterally in a back feeding direction to its initial position a distance equal to the total of the length of a stitch plus the distance the awl moved idly prior to penetrating the work. The awl then rises further to its fully retracted inoperative position.

The needle commences to descend toward the

awl hole substantially at the same time as the awl is lifted from the work and continues to descend while the awl, and its actuating arm, are being back fed out of its path. By the time the

needle point approaches closely to the work, the awl will have been back fed well away from beneath the needle and the latter may therefore continue its downward movement through the awl hole and into the internal work support without interference from the awl mechanism.

The needle and awl actuating arms are rotatably mounted, in side by side relation, on horizontal transverse bearings in the head of the machine, the needle actuating arm being normally held against movement axially of its bearing though being adjustable along it, and an awl supporting portion of the awl actuating arm sliding bodily along its bearing during idle and work feeding movements of the awl. Each of these arms is oscillated in the desired time relation to other instrumentalities of the machine and in a plane perpendicular to the axis of the bearings, by a cam acting on the rear end of the awl arm. The awl arm is formed in two parts, one for supporting the awl and the other for actuation by the cam, between which parts relative sliding movement may take place axially of the said bearing. For imparting the desired idle and work feeding movements to the awl at the desired times before and after it has penetrated the work, that part of its actuating arm which carries the awl is coupled to the forward end of a rocking shaft which extends forwardly and rearwardly of the machine, i. e. at right angles to the said bearing. This rocking shaft is rocked about its axis by a cam and its rocking movements are translated into lateral sliding movements of the awl through an offset block which couples a crank pin on the forward end of the shaft to a horizontal transverse feed slide having a forwardly extending tongue engaging a groove formed in the hub of the awl supporting part of the awl actuating arm. With this arrangement the awl actuating arm may be oscillated about its bearing by its cam and the awl supporting part of said arm may be moved at the same time laterally of the machine by the rocking shaft.

In order to provide for a variation in the length of stitches to be sewn, and therefore to enable adjustment to be made in the extent to which the awl feeds the work toward the needle after having penetrated it, the offset block which couples the crank pin to the feed slide is received within a slot in a relatively fixed but angularly adjustable member on the feed slide. This member is offset heightwise and laterally relatively to the axis of the rocking shaft. Rotation of said member may swing the slot into a chosen angular relation both to a line drawn perpendicular to the direction of work feed and to the path of movement of the crank pin, this angular relation determining the extents of movement imparted to the feed slide while the crank pin rocks from one side to the other of a line perpendicular to the direction of feed and of movement of the feed slide axially of the rocking shaft. When, for example, the slot lies at an angle of, say, thirty degrees to said perpendicular line and its upper end lies forwardly of said line considered in the direction of movement of the slide, the forward rocking movement of the crank pin, which lies in front of said adjustable member before the feed slide commences its lateral movement toward the needle and behind it when it has completed such movement, will cause the feed

slide to move laterally at a slower rate than the crank pin until a crank pin reaches the top of its rocking movement and will then cause the slide to move at a more rapid rate, and through a somewhat greater distance, than the crank pin as the latter swings downwardly and forwardly to complete its arcuate rocking movement. The crank pin is caused to dwell for a period at the top of its rocking movement and the awl is caused to descent toward the work during this dwell. Therefore, when the slot occupies such an inclination as just referred to, the work feeding movements of the awl will cause the machine to sew relatively long stitches.

If, now, it is desired to sew relatively short stitches, the angularly adjustable member is rotated to cause the slot to occupy a rearwardly inclined relation to a line drawn perpendicularly to the direction of movement of the feed slide. In such a case, since the slot will then lie more nearly perpendicularly to the path in which the crank pin moves at the commencement of its rocking movement and more nearly parallel to the path in which the crank pin moves after having reached its uppermost point, the feed slide will be moved laterally through a greater distance before the awl penetrates the work and through a shorter distance when the awl moves the work toward the needle after having penetrated it. Whatever be the angular setting of the slot, the feed slide moves the same over-all distance in each stitch forming cycle and brings each awl hole unvaryingly directly below the point of the needle.

Thus the illustrative machine includes a very compact and reliable arrangement by which ready variation may be made in the lengths of the stitches to be sewn by the machine at a given time without affecting the alignment of the awl hole with the needle path.

These and other features and advantages of the invention as hereinafter described and claimed will be readily apparent from the following specification taken in connection with the accompanying drawings, in which

Fig. 1 is a right hand side elevation of a portion of the illustrative machine;

Fig. 2 is a front elevation of the parts of the machine shown in Figure 1;

Fig. 3 is a section on the line III—III in Fig. 1;

Fig. 4 is a plan view of the parts of the machine shown in Figs. 1 and 2;

Fig. 5 is a right hand side elevation of parts of a work-feeding mechanism of the illustrative machine;

Fig. 6 is a section on the line VI—VI in Fig. 3;

Figs. 7 and 8 are diagrammatic views illustrating the operation of the work-feeding mechanism;

Fig. 9 is a right hand side elevation, partly in section, of parts of needle mechanism of the illustrative machine;

Fig. 10 is a view of the parts shown in Fig. 9 viewed in the direction of the arrow in that figure; and

Fig. 11 is a diagram or chart illustrating the timing in a sewing cycle of the machine of the awl and needle.

The illustrative machine, except as will hereinafter appear, is similar to the lockstitch McKay type machine disclosed in the Gouldbourn et al. patent above identified. Referring to the drawings, a curved awl 1 is clamped in the front end portion of an awl actuating arm or carrier 3 arranged to be moved downwardly and upwardly

about a horizontal axis 5 (Fig. 1) extending laterally of the machine and lying about five inches behind the awl and about one-quarter of an inch higher than the upper surface of a rotary horn 7 having a needle receiving hole and needle threading mechanism (not shown) at its upper end, corresponding to the horn referred to as a shoe-entering horn 15 in said patent. The aforesaid axis 5 is located in the machine in the same position as the axis referred to as the axis 65 in said patent. When viewed from the front of the machine the curvature of the awl 1 defines a vertical plane and when viewed from the side of the machine the curvature of the awl is concentric to the aforesaid axis 5 about which the awl arm 3 is arranged to be moved.

The rear end of the awl arm 3 has formed on it a sleeve 9 (Fig. 3) which extends to the right and is rotatably and slidably mounted in a sleeve 11 of a bearing 13 which is secured to a bracket 15 fixed on the frame of the machine head 17, which bracket carries a cover 18 to shroud the parts carried by the bracket from below. Rotatably mounted on the said sleeve 11 of the bearing is a rearwardly extending awl cam arm 19 arranged to move the awl arm 3 downwardly and upwardly about its axis 5. The rear end of the awl cam arm 19 has rotatably mounted on it a cam roll 21 arranged to engage a groove in a cam 23 secured on a horizontal cam shaft 25 rotatably mounted in the head 17 of the machine in front of and a little higher than a driving shaft 27 corresponding to the crank-shaft referred to as the crankshaft 29 in the prior patent. The cam shaft 25 is driven by the shaft 27, through gears, 29, 31, connecting the two shafts, the two shafts 25, 27 being driven at the same speed.

The front end of the awl cam arm 19 has extending upwardly from it a flange 33 extending across which is a recess 35 arranged to receive a lug 37 projecting toward the right from the awl arm 3. This connection between the awl arm 3 and the cam arm 19 allows the awl arm 3 to be oscillated by the cam arm 19 and the awl arm 3 to move laterally relatively to the cam arm 19 to feed the work when the awl 1 is in engagement therewith.

Referring to Figs. 3, 5 and 6, a flange on the awl arm 3 has in its lower edge a groove 41 (Fig. 3) extending part way around the axis of the arm. The groove 41 is engaged by a tongue 43 extending forwardly from a feed block 45 (Fig. 5) which is secured on a feed slide 47 extending laterally of the machine and slidably mounted in guideways 49 formed in rearward extensions of the aforesaid bearing 13 and of a corresponding similarly shaped bearing 51 (Fig. 3) which is also fixed to the bracket 15. The feed slide 47 is held in the guideways 49 by thin plates 56 secured to the bearings 13 and 51. The feed slide 47 is reciprocated to and fro laterally of the machine to cause, through the feed block 45, the awl arm 3 to move laterally of the machine and the awl 1, when it is in engagement with the work, to feed the work. The feed block 45 is secured to the feed slide 47 by a bolt 53 which passes through a slot in the feed block 45 extending lengthwise of the feed slide, so that the feed block 45 may be adjusted laterally of the machine on the feed slide 47 to ensure that the hole made in the work by the awl 1 will, at the end of the work feeding movement of the awl, be in alignment with the hole in the top of the horn and therefore in correct position to receive the needle 55.

The feed slide 47 has extending rearwardly from it a boss 57 (Fig. 5) in which is mounted a cylindrical feed-controlling member 59. The feed-controlling member has a stem 61 rotatable in the boss 57 about an axis 63 which extends rearwardly and slightly downwardly. On the rear end of the stem of the feed-controlling member is a flange 65 and formed diametrically in the rear face of the flange is an upwardly and downwardly extending rectangular groove 67. The stem 61 of the feed-controlling member has formed in it at the right hand side portion of its peripheral face a number of notches 69 (Fig. 4) and a spring-pressed plunger 71 slidably mounted in the boss 57 is arranged to engage one or another of the notches to hold the feed-controlling member 59 yieldingly in adjusted position about the axis of the stem 61. The rectangular groove 67 has slidably mounted in it a die-block 73 which is pivotally mounted on a crank pin 75 formed on the forward end of a feed shaft 77 rotatably mounted in the head 17. The feed shaft 77 extends rearwardly and slightly downwardly from its forward end at the same angle as the aforesaid axis 63 of the stem 61 and is lower than the axis of the crank pin 75 and the stem 61 of the feed-controlling member 59. The feed shaft 77 at its rear end portion has an upwardly extending arm 79 (Fig. 1) having on its upper end portion a rearwardly extending pin 81 on which is rotatably mounted a roll 83. The roll 83 engages a groove 85 in the periphery of a feed cam 87 secured on the driving shaft 27.

The feed shaft 77 is oscillated by the feed cam 87 and through the feed-controlling member 59 reciprocates the feed slide 47 and awl arm 3 a distance more than the length of a stitch toward and from the path of the needle laterally of the machine to cause the awl 1 to feed the work, when in engagement therewith, and to return when the awl has been moved upwardly away from the work. The crank pin 75 on the feed shaft 77 is actuated at two separate times during each sewing cycle an equal distance, about one quarter of an inch, each side of a vertical plane passing through the axis of the feed shaft 77. When the crank pin 75 is at either end of its movement across said vertical plane its axis is in alignment with the axis 63 of the adjustable feed-controlling member 59 and therefore the feed-controlling member 59, feed slide 47 and awl 1 are all moved uniformly the same distance laterally of the machine by the crank pin 75 in each portion of the total movement. If the groove 67 in the feed-controlling member 59 is vertical movements of the feed-controlling member laterally in the direction of work feed will correspond to movements of the crank pin 75, the die-block of course moving upwardly and downwardly in the groove since the crank pin moves in a curved path about the axis of the shaft 77 whereas the feed-controlling member 59 moves in a straight horizontal path. If, however, the feed-controlling member 59 is rotatably adjusted about the axis 63 of its stem 61 so that the groove 67 therein is not vertical, horizontal movements of the feed-controlling member 59 at either side of a central position of the crank pin 75 will not be equal and will not correspond to movements of the crank pin, i. e. if the groove 67 is at an angle extending upwardly toward the aforesaid vertical plane passing through the axis of the feed shaft 77, as shown in Fig. 7, the feed-controlling member 59 will lag behind

the crank pin 75 during the first part of its movement, owing to the die block 73 moving upwardly in the inclined groove 67 as it moves laterally with the crank pin 75. Thus, the movement in the direction of work feed imparted to the feed-controlling member 59 and awl 1 during the first part of the movement of the crank pin will be relatively slow compared to the movement of the crank pin until the die block 73 begins to move down the groove whereupon the feed-controlling member 59 begins to catch up with the crank pin 75 and the movement of the controlling member and awl will be increased until at the end of the movement of the crank pin 75 the axes of the crank pin 75 and feed-controlling member 59 are once more in alignment.

When the feed-controlling member 59 is in the position shown in Fig. 7 the feed-controlling member 59 will be moved from A to B while the crank pin 75 is moving from A to C and while the crank pin is moving from C to D the feed-controlling member will be moved from B to D. The actual feed of the work by the awl 1 takes place while the crank pin is moving from C to D.

If the groove 67 in the feed-controlling member 59 is inclined in the opposite direction, as shown in Fig. 8, the reverse action takes place as regards the movement of the feed-controlling member 59 in relation to the movement of the crank pin 75. Thus, during the first part of the movement of the crank pin from E to F the feed-controlling member 59, instead of lagging behind the crank pin moves in advance thereof from E to G and as the crank pin 75 moves from F to H the feed-controlling member 59 moves from G to H, the crank pin catching up with the feed-controlling member until their axes are again in alignment. In this way movement of the awl will at first be relatively rapid and then slower compared to the movement of the crank pin.

As will hereinafter appear, the feed of the work takes place during the latter part only of the lateral movement of the awl toward the needle. The first part of the movement of the awl is an idle movement from a position more than a stitch length away from the needle to a position a stitch length away from the needle, the awl being disengaged from the work, for a purpose hereinafter described. By comparing Figs. 7 and 8 it will be apparent that when the controlling member is in the position shown in Fig. 7 the latter part of the feeding movement of the awl will cause the work to be fed a longer distance than when the feed-controlling member 59 is in the position shown in Fig. 8.

If the feed-controlling member is adjusted to provide a relatively short stitch, e. g. one-seventh of an inch, the feeding movement of the awl, when it has engaged the work, will occupy only a relatively small portion of the total movement of the awl toward the needle and the idle part of the movement of the awl toward the needle will be relatively long. If the feed-controlling member is adjusted to provide a relatively long stitch, e. g. one-quarter of an inch, the idle movement of the awl is reduced in comparison with the actual feeding movement of the awl.

The particular construction of the feed and feed-adjusting mechanism just described provides a robust, compact and uncomplicated arrangement, occupying only a relatively small

space in the machine and being free from undue wear and undesirable spring in the parts.

The hook needle 55 of the illustrative machine is, when viewed from the side of the machine, curved about the same axis 5 as the awl 1 and when viewed from the front its axis lies in a vertical plane. The needle 55 is secured in the front end portion of a needle actuating arm or carrier 89 the rear end portion of which has extending horizontally to the left from it a sleeve 91 (Fig. 3) the axis of which is in alignment with the aforesaid sleeve 9 on the awl arm 3. The sleeve 91 on the needle arm is rotatable in a sleeve 93 of the aforesaid bearing 51 which is secured to the aforesaid bracket 15 to which the aforesaid bearing 13 of the awl arm 3 is secured.

The lower portion of the needle arm 89 has formed in it a groove 95 extending part way around the axis of the arm, which groove 95 receives a tongue 97 (see Figs. 9 and 10) on a block 99 secured to the bracket 15. The tongue block 99 is secured to a bracket 101 which in turn is secured, by screws 103, to the bracket 15. The tongue block 99 is secured to the bracket 101 by two bolts 105. The bolts 105 pass through open-ended slots 107 in the bracket 101 and have on them heads 109 which engage undercut recesses in the bracket. When the bolts 105 are loosened the tongue block may be adjusted laterally of the machine to bring the needle into alignment with the hole in the top of the horn. For so adjusting the tongue block 99 the block has rotatably mounted in it a stud 111 having an eccentric portion 113 arranged to engage a recess 115 (Fig. 10) in the bracket 101.

Rotatably mounted on the sleeve portion of the bearing 51 is a needle-cam arm 117 (Figs. 1 and 4). The needle-cam arm 117 has an upwardly extending portion 119 in which is formed a recess 121 (Fig. 3) arranged to receive a lug 123 projecting laterally from the needle arm 89, the recess 121 and lug 123 being similar to the recess 35 and lug 37. The needle-cam arm 117 through the lug 123 and recess 121, causes the needle arm 89 to oscillate about its axis and the lug 123 and recess 121 allow the needle arm 89 to be adjusted laterally relatively to the needle-cam arm 117. The needle-cam arm 117 has on its rear end a roll 125 arranged to engage a cam groove in the cam 23 which causes the needle to move downwardly and upwardly.

To stiffen the feed slide arrangement and positively prevent misalignment of the needle and awl carriers, a shaft 127 extends through the sleeves 9 and 91 of the awl and needle arms and is secured to the awl arm 3. This shaft provides support for the arms against twisting thereof.

When the needle arm 89 is moved downwardly and upwardly the needle 55 remains in the same plane without lateral movement. The awl arm 3 is moved downwardly and upwardly and also laterally to carry a hole made in the work beneath the needle. The awl and needle arms, as will be apparent, lie side by side and their forward end portions are curved inwardly toward each other, as shown in Fig. 4, so that the awl may move beneath the needle when the latter is raised.

The timing of the awl and needle of the illustrative machine will now be described, with reference to the chart of Fig. 11 in which the line A represents the up and down movement of the needle, the line B represents the up and

down movement of the awl, and the line C represents the lateral movement of the awl. Assuming the illustrative machine to be in operation to sew a seam and the work-feeding and stitch-forming devices to have reached once more the positions which they occupied when the machine came to rest, the awl will be at the right of its path of lateral movement and will have moved downwardly, about one-quarter of its movement toward the work. The needle (line A) will be rising and nearly at the top if its movement away from the work. During about the first 15° of rotation of the driving shaft the awl (line B) moves downwardly to a position about half-way toward the work where there is a dwell 131 in the downward movement, the awl having moved slightly toward the left. The needle during this 15° of rotation of the driving shaft moves nearly to its highest position. During about the next 15° of rotation of the driving shaft the awl remains in this heightwise position. Thereafter the awl is moved laterally (line C) part way toward the left, the needle rising to the top of its heightwise movement and there is a dwell 133 in the feed. During about the next 30° of rotation of the driving shaft during the dwell 133 the awl is moved fully downwardly into the work, until its lower end is a little higher than the top of the horn, the needle moving downwardly slightly from its fully raised position. During about the next 70° of rotation of the driving shaft the awl is lifted slightly from its fully lowered position to relieve pressure of the work on the horn caused by the piercing action of the awl and is moved to the left to feed the work, the needle remaining substantially in its raised position. The awl then is in a position beneath the needle and in alignment with the hole in the upper end portion of the horn. During about the next 20° of rotation of the driving shaft there is a dwell 135 in the feed and the awl remains in its left-hand position beneath the needle, which remains in its raised position. Thereafter the awl moves upwardly out of the work to a position about half-way heightwise of its upward movement. During about the next 30° of rotation of the driving shaft there is a dwell 137 in the upward movement of the awl and it remains substantially in its last-mentioned heightwise position and moves to the right from beneath the needle into its extreme right-hand position more than a stitch length away from the path of the needle, the needle commencing to move downwardly from its fully raised position.

During about the next 25° of rotation of the driving shaft the awl, while it remains at the right-hand end of its lateral position, is fully raised, the needle continuing to move downwardly. During about the next 140° of rotation of the driving shaft the awl remains in its right-hand and fully raised position and the needle fully descends and commences to rise again. During the next and last 15° of rotation of the driving shaft the awl descends about to its starting position while remaining in its right-hand position. The needle continues to descend and reaches its lowest position when the driving shaft has rotated about 265° from its starting position. The needle remains in its lowered position during about the next 45° of rotation of the driving shaft, during which the needle thread is wrapped around the needle by the whirl in the horn, and the needle then rises during about the

last 50° of rotation of the driving shaft to its starting position.

From the foregoing it will be apparent that the awl while in its right-hand position is moved downwardly part way toward the work. While in the part-way downward position there is a dwell while it is moved part way toward the needle within a stitch length of the needle which has been raised out of the way of the awl and awl arm. The awl is then moved further downwardly into engagement with the work and is then moved to the left to feed the work. In doing so it moves beneath the needle which is in its raised position. Having fed the work to a position in which a hole made in the work by the awl is above the hole in the upper end of the horn and in a position to receive the needle when it descends, the awl, while remaining in its left-hand position is raised out of the work about half-way toward its fully raised position where there is a second dwell. During this second dwell the awl is moved to its right-hand position, out of the way of the needle, before being fully raised out of the way of a thread lifter similar to the thread lifter indicated at 155 in the Gouldbourn et al. patent.

The distance the awl moves toward the left before it is moved downwardly into engagement with the work will, of course, vary with the adjustment of the feed since the feeding of the work takes place after the awl has engaged the work, the awl moving further toward the left before it engages the work if the feed of the work is relatively short than if it is relatively long. The same is true of the disengagement of the awl from the work. The dwells 133 and 135 are for the purpose of preventing time variations in lateral movement of the awl from affecting the position of the awl when adjustments are made. The dwells 131 and 137 in the downward and upward strokes of the awl are to enable the awl carrier to move beneath the needle carrier and thread lifter.

While the several features of the invention are herein disclosed as applied to a McKay type lock-stitch sewing machine provided with a rotatable work supporting horn, it is to be understood that certain features of the invention are of more general application to shoe sewing machines of other types and for operating to advantage on other than McKay type shoes.

The invention having thus been described, what is claimed as new and desired to be secured by Letters Patent of the United States is:

1. A shoe sole sewing machine having a curved hook needle mounted to oscillate toward and from the work about a transverse axis and other stitch forming devices, in combination with a curved work feeding awl at the side of the work with the needle and oscillating about the same axis as the needle and mechanism for actuating the awl with an idle lateral movement before it engages the work to carry it closer to the plane of the needle.

2. A shoe sole sewing machine having a curved hook needle mounted to oscillate toward and from the work about a transverse axis and other stitch forming devices, in combination with a curved work feeding awl at the side of the work with the needle arranged for oscillation about the same axis as the needle and mechanism for actuating the awl with an idle lateral movement before it engages the work to carry it close to the plane of the needle when the needle is retracted from the work, and after engaging the work to

feed the work toward the plane of the needle until the awl hole in the work is moved directly beneath the needle point.

3. A shoe sole sewing machine having a curved hook needle mounted to oscillate toward and from the work and other stitch forming devices, in combination with a work feeding awl at the side of the work with the needle and mechanism for actuating it with two separate lateral movements in the direction of feed, the first of which is while disengaged from the work and while the needle is retracted from the work, and the second of which is after engagement with the work for feeding the work to enable the awl to penetrate the work between said lateral movements at a point close to the plane of the needle.

4. A shoe sole sewing machine having a curved hook needle, a needle carrier mounted to oscillate toward and from the work, a curved work feeding awl at the side of the work with the needle and other stitch forming devices, and a carrier arm for the awl mounted to oscillate concentrically with the needle, in combination with mechanism for actuating the awl carrier arm with two separate lateral movements in the direction of feed, the first of which brings the awl carrier arm into underlying relation to the needle carrier arm to enable the awl to be brought close to the plane of the needle, and the second of which causes the awl to feed the work.

5. A shoe sole sewing machine having a curved hook needle, a needle carrier arm mounted to oscillate toward and from the work, a curved work feeding awl at the side of the work with the needle and other stitch forming devices, a carrier arm for the awl mounted to oscillate concentrically with the needle in combination with mechanism for actuating the awl carrier arm with two separate lateral movements in the direction of feed, the first of which brings the awl carrier arm into underlying relation to the needle carrier arm to enable the awl to be brought close to the plane of the needle, and the second of which causes the awl to feed the work, and mechanism for actuating the awl to pierce the work at the conclusion of its first lateral movement so that the hole formed by the awl may be brought into alignment with the needle for entry of the needle when it descends.

6. A shoe sole sewing machine having a curved hook needle, a needle carrier arm mounted to oscillate toward and from the work, a curved work feeding awl and other stitch forming devices, a carrier arm for the awl mounted to oscillate concentrically and at the same side of the work with the needle, in combination with mechanism for actuating the awl carrier arm with two separate lateral movements, the first of which brings the awl carrier arm into underlying relation to the needle carrier arm to enable the awl to be brought close to the plane of the needle, and the second of which causes the awl to feed the work, mechanism for actuating the awl to pierce the work at the conclusion of its first lateral movement so that the hole formed by the awl may be brought into alignment with the needle for entry of the needle when it descends, said mechanism causing the awl to pause, with a dwell in its lateral movement while engaging the work when the awl is in alignment with the needle, and means for clamping the work during said dwell.

7. A shoe sole sewing machine having a curved hook needle, a curved work feeding awl and other stitch forming devices, a work support and

13

a presser foot in combination with mechanism for actuating the awl to penetrate and withdraw from the work, and mechanism for imparting a lateral movement to the awl in the direction of work feed, said mechanisms acting while the work is clamped between the work support and presser foot to cause the awl to retract sufficiently to withdraw it from the work, to move laterally in a back feeding direction a distance equal to the length of a stitch, then to move idly still further away from the needle and thereafter to rise further away from the work to a fully retracted inoperative position.

8. A shoe sole sewing machine having a curved hook needle, a curved awl and other stitch forming devices, a work support and a presser foot in combination with mechanism for actuating the awl to penetrate and withdraw from the work, mechanism for imparting a lateral movement to the awl in the direction of feed, said mechanisms acting while the work is clamped between the work support and presser foot to cause the awl to retract sufficiently to withdraw it from the work, to move laterally in a back feeding direction a distance equal to the length of a stitch and then to move idly still further away from the needle and thereafter to rise further away from the work to a fully retracted inoperative position, and mechanism for actuating the needle to cause it to enter a hole formed by the awl after the idle movement of the awl is started.

9. A shoe sole sewing machine having a curved hook needle and a work support, in combination with a curved work feeding awl arranged at the same side of the work with the needle and mechanism for actuating the awl to move it in the direction of feed toward the needle as the needle is retracting from the work during each sewing cycle and thereafter to move it more than a stitch length away from the path of the needle.

10. A lockstitch shoe sewing machine having a hook needle, a work feeding awl, carrier arms in which the needle and awl are arranged for movement toward and from the work, and mechanisms for actuating the needle and awl to cause them to penetrate and retract from the work, in combination with mechanism connected to the awl carrier arm acting before the awl pierces the work to move the awl laterally in the direction of feed idly before engaging the work, and an adjustable connection in said awl feeding mechanism for changing the idle lateral movement of the awl.

11. A lockstitch shoe sewing machine having a hook needle, a work feeding awl, carrier arms in which the needle and awl are arranged for movement toward and from the work, and mechanisms for actuating the needle and awl to cause them to penetrate and retract from the work in combination with mechanism connected to the awl carrier arm acting before the awl pierces the work to move the awl laterally in the direction of feed idly before engaging the work, and an adjustable connection in said awl feeding mechanism for changing the idle lateral movement of the awl with relation to the feeding movement while the total of the idle and work feeding movements of the awl remains unchanged.

12. A lockstitch shoe sewing machine having a hook needle, a work feeding awl, carrier arms in which the needle and awl are arranged for movement toward and from the work, and mechanisms for actuating the needle and awl to cause them to penetrate and retract from the work, in com-

bination with mechanism acting to impart two separate lateral movements to the awl carrier arm in the direction of work feed, one of which takes place idly before the awl engages the work and the other after the awl pierces the work.

13. A lockstitch shoe sewing machine having a hook needle, a work feeding awl, carrier arms in which the needle and awl are arranged for movement toward and from the work, and mechanisms for actuating the needle and awl to cause them to penetrate and retract from the work, in combination with mechanism acting to impart two separate lateral movements to the awl carrier arm in the direction of work feed, one of which takes place idly before the awl engages the work and the other after the awl pierces the work, including an adjustable feed controlling member arranged to increase the length of the lateral movement of the awl after engaging the work and simultaneously to decrease the length of the idle movement.

14. A shoe sole sewing machine having a curved hook needle and a work feeding awl both located at the same side of the work, in combination with mechanisms for moving the awl into engagement with the work and in the direction of work feed to feed the work in each stitch forming cycle and for causing the awl to engage the work only after it has moved a predetermined distance idly toward the plane of the needle.

15. A shoe sole sewing machine having a curved hook needle and a work feeding awl both located at the same side of the work, means for oscillating the needle toward and from the work and for retaining it against transverse movement, means for oscillating the awl toward and from the work, and mechanism for moving the awl idly in a lateral direction before engaging the work to cause it to be interposed between the work and the needle when the latter is retracted from the work.

16. A shoe sole sewing machine having a curved hook needle and a work feeding awl both located at the same side of the work, carriers for the needle and awl, and mechanism for moving the awl along the line of work feed into such close proximity to the path of the needle prior to commencing to feed the work and while the needle is in a retracted position out of the work, that the awl carrier then partially occupies a space normally occupied by the needle carrier when the needle is in engagement with the work.

17. A shoe sole sewing machine having a curved hook needle and a work feeding awl both located at the same side of the work and separate mechanisms acting successively in each stitch forming cycle to retract the needle from the work, to move the awl in the direction of work feed toward the needle, thereafter to move the awl into engagement with the work and to move the awl in the direction of work feed until a hole made in the work by the awl is brought directly beneath the needle point.

18. A shoe sole sewing machine having a curved hook needle and a work feeding awl both located at the same side of the work, in combination with mechanism for imparting equal lateral movements to the awl during successive sewing cycles comprising a feed slide, a grooved member on the feed slide, an oscillating member having sliding engagement with the grooved member, and means for adjusting the angular relation of said grooved member and the path of movement of the oscillating member to vary the extent of lateral movement imparted to the feed slide during a part of the rocking movement of the oscillating member.

19. A shoe sole sewing machine having a curved hook needle and a curved work feeding awl, both operating at the same side of the work, a feed slide, in combination with mechanism for imparting equal lateral movements to the feed slide during successive sewing cycles with parts of said movements relatively adjustable in length, comprising a rotatable grooved feed controlling member on the feed slide, an oscillating member having slidable engagement with the grooved member and being actuated during each sewing cycle from a position in alignment with the axis of rotation of the grooved member at one end of the oscillating movement of the oscillating member to a position in alignment with the axis of rotation of the grooved member at the other end of said oscillating movement, and means for holding the grooved member in fixed position on the feed slide about its axis of rotation.

20. A shoe sole sewing machine having a curved hook needle and a curved work feeding awl, both operating at the same side of the work, a feed slide, in combination with mechanism for imparting equal lateral movements to the feed slide during successive sewing cycles with parts of said movements relatively adjustable in length, comprising a rotatable grooved feed controlling member on the feed slide, an oscillating feed shaft, a crank pin on the feed shaft, a die-block on the crank pin engaging the groove in the grooved member, said crank pin being actuated during each sewing cycle from a position of alignment with the axis of rotation of the grooved member at one end of the oscillating stroke of the die-block to a position of alignment with said axis at the other end of said oscillating movement, and means for holding the grooved member in fixed position on the feed slide about its axis of rotation.

21. A shoe sole sewing machine having a curved hook needle and a curved work feeding awl, both operating at the same side of the work, a feed slide, in combination with mechanism for imparting equal lateral movements to the feed slide during successive sewing cycles with parts of said movements relatively adjustable in length, comprising a rotatable grooved feed controlling member on the feed slide, an oscillating feed shaft, a crank pin on the feed shaft, a die-block on the crank pin engaging the groove in the grooved member, said crank pin being actuated during each sewing cycle from a position of alignment with the axis of rotation of the grooved member at one end of the oscillating stroke of the die-block to a position of alignment with said axis at the other end of said oscillating movement, and spring-pressed plunger and notch means for yieldingly holding the grooved member in fixed position on the feed slide.

22. A McKay type shoe sewing machine having a curved hook needle, a carrier on which the needle is mounted for movement toward and from the work in a fixed path, a work feeding awl, an awl carrier movable in the direction of work feed, bearings on which said carriers are mounted, a rotary work supporting horn and an oscillating feed shaft, the oscillating movements of which are translated into lateral movements of the awl carrier in the direction of work feed in combination with feed adjustable connections between the awl carrier and the feed shaft comprising a crank pin on the feed shaft, a rotatable grooved feed controlling member, a die-block on the crank pin slidable in the groove of the controlling member, and means for retain-

ing the feed controlling member against rotation on the feed slide.

23. A McKay type shoe sewing machine having a curved hook needle, an oscillating carrier arm on which the needle is mounted for movement toward and from the work, a curved work feeding awl, an oscillating carrier arm movable in the direction of feed on which the awl is mounted, bearings on which said carrier arms are mounted, a rotary work supporting horn and an oscillating feed shaft, the oscillating movements of which are translated into lateral movements of the awl carrier arm in the direction of work feed, in combination with feed adjusting connections between the awl carrier arm and the feed shaft comprising a crank pin on the feed shaft, a rotatable grooved feed controlling member, and a die-block on the crank pin slidable in the groove of the controlling member.

24. A shoe sole sewing machine having a curved hook needle, a needle carrier, an awl, an awl carrier, aligned bearing sleeves within which said carriers rotate and along which said awl carrier slides, in combination with means rotatably mounted on said sleeves and connected to the respective carriers for moving the needle and awl toward and from engagement with the work.

25. A shoe sole sewing machine having a curved hook needle, a grooved needle carrier, a curved awl, a grooved awl carrier and aligned bearing sleeves within which said carriers rotate and along which said awl carrier slides, in combination with cam arms rotatably mounted on the bearing sleeves, connecting means between the respective carriers and the cam arms including cooperating lug and recess portions on said carriers, and tongues engaging the grooves in the respective carriers to maintain the carriers in correct lateral position relatively to each other

40 along the bearings.

26. A shoe sole sewing machine having a curved hook needle, a grooved needle carrier, a curved awl, a grooved awl carrier and aligned bearing sleeves within which said carriers rotate and along which said awl carrier slides, in combination with cam arms rotatably mounted on the bearing sleeves, connecting means between the respective carriers and the cam arms including cooperating lug and recess portions on said carriers, a tongue block adjustably secured to the machine engaging the groove in the needle carrier, a second tongue block engaging the groove in the awl carrier, and a feed slide to which is adjustably secured the awl carrier engaging tongue block.

27. A shoe sole sewing machine having a curved hook needle, a grooved needle carrier, a curved awl, a grooved awl carrier and aligned bearing sleeves within which said carriers rotate and along which said awl carrier slides, in combination with cam arms rotatably mounted on the bearing sleeves, connecting means between the respective carriers and the cam arms including cooperating lug and recess portions on said carriers, a tongue block adjustably secured to the machine engaging the groove in the needle carrier, a second tongue block engaging the groove in the awl carrier, a feed slide to which is adjustably secured the awl carrier engaging tongue block, and mechanism for reciprocating the feed slide laterally the same distance during successive sewing cycles including adjustable connections with the feed slide for varying the distance through which the feed slide is recipro-

cated in one part of a stroke relatively to another part.

28. A shoe sole sewing machine having a curved hook needle, a grooved needle carrier, a curved awl, a grooved awl carrier and alined bearing sleeves within which said carriers rotate and along which said awl carrier slides, in combination with cam arms rotatably mounted on the bearing sleeves, connecting means between the respective carriers and the cam arms including cooperating lug and recess portions on said carriers, a tongue block adjustably secured to the machine engaging the groove in the needle carrier, a second tongue block engaging the groove in the awl carrier, a feed slide to which is adjustably secured the awl carrier engaging tongue block, mechanism for reciprocating the feed slide laterally the same distance during successive sewing cycles including adjustable connections with the feed slide for varying the distance through which the feed slide is reciprocated in one part of a stroke relatively to another part, a cam for actuating the awl cam arm to cause the awl to engage the work during one only of said parts of the feed slide stroke, and a cam for actuating the feed slide reciprocating mechanism formed with dwells to hold the feed slide stationary while the awl engages and disengages the work.

29. A shoe sole sewing machine having a curved hook needle, a grooved needle carrier, a curved awl, a grooved awl carrier and alined bearing sleeves within which said carriers rotate and along which said awl carrier slides, in combination with cam arms rotatably mounted on the bearing sleeves, connecting means between the respective carriers and the cam arms including cooperating lug and recess portions on said carriers, a tongue block adjustably secured to the machine engaging the groove in the needle carrier, a second tongue block engaging the groove in the awl carrier, a feed slide to which is

5 adjustably secured the awl carrier engaging tongue block, mechanism for reciprocating the feed slide laterally the same distance during successive sewing cycles including adjustable connections with the feed slide for varying the distance through which the feed slide is reciprocated in one part of a stroke relatively to another part, a cam for actuating the awl cam arm to cause the awl to engage the work during one only of said parts of the feed slide stroke, and a cam for actuating the feed slide reciprocating mechanism formed with dwells to hold the feed slide stationary while the awl engages and disengages the work.

10 15 30. A shoe sole sewing machine having a curved hook needle mounted to oscillate toward and from the work about a transverse axis and other stitch forming devices, in combination with a curved work feeding awl at the side of the work 20 with the needle, mechanism for actuating the awl along the line of feed a uniform distance, a portion of which is idle while the awl is disengaged from the work, and connections in said mechanism for varying the length of the stitches 25 inserted by changing the extent of idle movement of the awl in the direction of feed before it engages the work.
